UNITED STATES PATENT OFFICE.

L. ATWOOD, OF BROOKLYN, NEW YORK.

IMPROVEMENT IN MANUFACTURE OF PYROGENIC OILS.

Specification forming part of Letters Patent No. 22,406, dated December 28, 1858.

To all whom it may concern:

Be it known that I, LUTHER ATWOOD, of the city of Brooklyn, in the county of Kings and State of New York, have invented a new and useful method of manufacturing oils from bitumens, resins, schist, and fatty bodies that yield pyrogenic oils and that are soluble, or in part soluble, in the products of their decomposition, and that melt or intumesce during decomposition, also coal, peat, wood, and other substances yielding pyrogenic oils, which may be worked by this process; and I do hereby declare the following to be a full and exact description of my invention and the apparatus I use, reference being had to the annexed drawings, forming a part of this specification, in which—

Figure 6 represents a vertical longitudinal section of a form of apparatus I use, showing detached view of condenser broken off from pipe H; Fig. 7, horizontal section of Fig. 6 through dotted line 7; Fig. 8, horizontal section of Fig. 6 through dotted line 8; Fig. 9, transverse section of Fig. 6 through dotted line 9; Fig. 10, transverse section of Fig. 6 through dotted line 10; Fig. 11, longitudinal section of modification of Fig. 6; Fig. 12, horizontal section of Fig. 11 through dotted line 11.

Letter A, Fig. 6, represents a distilling-chamber with a suitable opening and stopper, B, for the purpose of charging and removing the residue.

A' is a fire-place or "combustion-tower," in which coke or other fuel is burned on grate G.

C is a man-hole stopped air-tight, used to clean out the ash pit or cavity D, which connects by passage E with the heating-flues F, which heat the floor Z of the distilling-chamber, and conduct the current of products of combustion induced by a jet of steam, let in at K, into the draft-pipe H from the combustion-tower into the distilling-chamber at E' E'', just behind the bridge-wall Z'. This hot current of the products of combustion on its way to the draft-pipe H passes over the bridge-wall Z' and strikes down onto the surface of the mass of bitumen or other substance to be decomposed, which is deposited on the floor between the bridge-wall and the opening B, and by the action of the heat decomposition is effected or assisted, and the vapors arising from decomposition are taken up by the current as they form and removed from the dis-

tilling-chamber through the draft-pipe H to the worm-condenser in the tub of water L, where the greater part of the crude oil is separated from the mixed current, the more volatile products of decomposition and the products of combustion escaping at O, after being washed by a jet of water from the rose of pipe P, the crude oil being collected in the dip-pipe M, and, passing around the diaphragm therein, flows out at Q, accompanied by water, from which it may be separated by permitting the whole to discharge into a vessel from which the water can pass out through a hole in the bottom, and the oil be drawn off at the top. X is a damper in passage E, which should be closed when the residue is removed, as should also the valve Y in the pipe H. The steam-jet pipe K is provided with a suitable valve, to control the force of the jet, as is also the water-jet P, and they are to be respectively connected in a suitable manner to a high-pressure steam-boiler and a fountain-head or force-pump. The object of the steam-jet being merely to induce a current, it may be placed at any convenient point where it will produce and properly control a current of products of combustion through the apparatus, say at the end of pipe O.

I would here state that though I prefer to use a steam-jet, because it is easily governed, I will adopt any known controllable means of inducing or impelling a properly-regulated current of the products of combustion through the apparatus and in contact with the surface of the body to be decomposed.

In the modification of the apparatus as shown in Figs. 11 and 12, the products of combustion pass directly into the distilling-chamber from the combustion-tower A' through the passage E E', the floor being heated, when desired, by the products of combustion from the furnace Y' passing through passage X' and heating-flues W'. This form is well adapted for substances that intumesce.

In my process I prefer to use the downward draft through the fire, because it affords facility of supplying fuel to the fire without admitting atmospheric air to the distilling-chamber, which would cause combustion to take place therein; but whatever combustion-chamber is used care must be taken to regulate the draft and fire, so that no more air passes in than is deprived of its free oxygen by the fire,

and that the chamber and opening and man-hole be stopped air-tight, except the openings for ingress and egress of the current of products of combustion. Care must also be taken to regulate the heat so that decomposition will take place at the lowest temperature or at a sufficiently low temperature to form oleaginous vapor and avoid the formation of the gases and volatile products which are the products of decomposition at high temperatures. The floor and sides of the distilling-chamber, which, as shown in the drawings, are built of brick, may be, when used for fluid substances, lined with metal; or the entire chamber may be made of metal.

Though I consider the method herein described as more particularly applicable to substances that melt during decomposition or are soluble in the products of their decomposition, and prefer the process I have described in a former specification for coals and similar substances, wherein the current of

products of combustion circulates through the mass to be decomposed, still it is evident that the above-described method can be used successfully to obtain pyrogenic oils from coal and the other bodies that can be worked by the former process.

What I claim as my invention, and desire to secure by Letters Patent of the United States, is—

Forming oleaginous vapors from substances yielding pyrogenic oils by the action of the heat of a properly-regulated current of products of combustion passing over and above the surface of the mass operated on, with or without the aid of external heat, substantially as hereinbefore described, and for the purposes hereinbefore set forth.

LUTHER ATWOOD.
